UNITED STATES PATENT OFFICE

FRED SUTCLIFFE, JR., OF PHILADELPHIA, PENNSYLVANIA, ASSIGNOR TO MOCK, JUDSON, VOEHRINGER COMPANY, INC., OF PHILADELPHIA, PENNSYLVANIA, A CORPORATION OF DELAWARE

WELT NEEDLE FOR KNITTING MACHINES

Application filed February 15, 1930. Serial No. 428,764.

The invention relates to an improved needle for knitting machines, especially adapted for turning welts and designed to enable even unskilled operators to perform that operation with facility and certainty of success and without impairment of the apparatus or the knitted product, to which end the needle comprises a shank with the usual butt at one end, a spring beard near 10 the opposite end and a pointed and curved end beyond the beard. The invention is illustrated in the accompanying drawings, in which:—

Fig. 1 is a side elevation of a typical 15 needle, the same being enlarged.

Fig. 2 is a top view of the same.

Fig. 3 is a bottom view.

Fig. 4 is a side elevation of a modification illustrating the mode of forming the needle.

Fig. 5 is a side elevation of the completed needle.

Fig. 6 is a plan view.

Referring to Figs. 1, 2 and 3, 1 indicates the shank of the needle provided with an 25 angularly disposed butt 2 at one end and a tapered, pointed and laterally curved outer end 3. One side of the needle is provided with the usual longitudinal groove 4 and the diametrically opposite side is provided with a spring beard, which, in the 30 form shown, is made up of a base section 5 of substantial channel shape, which terminates in the integral bent spring section 6, which constitutes the beard proper, 35 the end of which is adapted to be forced downwardly into the channel-like section 5 during the stripping operation. To facilitate the freeing of the loops from the needle, the upper edges of the channel-like member 40 5 are inclined in both directions, producing a hump-like effect over which the loops will readily pass. The member 5 is rigidly secured to the side of the needle opposite that which carries the longitudinal groove 45 4, preferably by welding.

Instead of forming the needle of two parts, which are welded together in the manner and form just described, it may be made of a single section of steel, as shown 50 in Figs. 4, 5 and 6, Fig. 4 indicating by

full lines the shape of the steel spindle in its initial straight form, in which the shank 1' is extended in a tapering forward section, the rear end of the shank being adapted to be bent to form a butt 2' and the forward end bent backward toward the body of the shank to constitute the spring beard, the end of which is adapted to be depressed into an eye or recess 5' common to needles of this character and the opposite side of the needle being provided with a longitudinal groove 4'. The end of the needle carrying the spring beard is first bent to the position shown in Fig. 4, in which the loop within the bend is fairly open, after 55 which the tip of the needle is reduced to the consolidated laterally bent point 3' by swaging or similar treatment, so that the outer end of the needle beyond the beard will have substantially the same form as 60 that shown in the first modification, namely, tapered to a point and bent laterally and in the opposite direction to the projection of the spring beard 6'.

In applying the improved needles to their 65 intended use, said needles, in requisite number, are mounted in series in the usual ledger bar in the manner and order of the ordinary welt hooks now employed, and the assembly is applied to the machine in place of the welt 70 bar assembly now in general use, and, when the welts are ready to be turned, the assembly may be readily engaged with the usual transfer device or rack in substantially the same manner that the common form of footer bar 75 is applied, with the important differences that drop stitches, resulting in seconds or impaired products, bending of needles, resulting in narrowing holes, are eliminated, and "press offs" are reduced to a minimum, even when 80 the operations are performed by persons who have little or no skill or experience in turning welts. In short, by substituting the new needle for the usual combination of welt hook 85 and transfer point, welts may be turned quickly and successfully, even by comparative tyros, without danger of bending or breaking needles or dropping stitches, thereby avoiding the difficulties of operation and imperfections in the products, as stated, and also 90 95 100

avoiding the necessary waste of time in training unskilled operators in the use of the old devices employed for turning welts.

What I claim is:

- 5 1. A welt needle for knitting machines comprising a shank, a spring beard near the outer end thereof, and a pointed and curved end beyond said beard.
- 10 2. A welt needle for knitting machines comprising a shank having a pointed and curved outer end and a spring beard to the rear of said end.

In testimony whereof I affix my signature.
FRED SUTCLIFFE, JR.
